UNITED STATES PATENT OFFICE.

ALFRED J. GILLESPIE, OF ATLANTIC, IOWA.

STRINGING PIANOS.

SPECIFICATION forming part of Letters Patent No. 275,818, dated April 17, 1883.

Application filed August 25, 1882. (No model.)

To all whom it may concern:

Be it known that I, ALFRED J. GILLESPIE, a citizen of the United States, residing at Atlantic, in the county of Cass and State of Iowa, have invented certain new and useful Improvements in Stringing Pianos; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has relation to improvements in the stringing of pianos.

It consists essentially in securing the piano-string in the eye of a pulley and passing a supplemental wire around the periphery of said pulley and drawing on said supplemental wire, as will be described, and in other improvements, all of which will be hereinafter fully described, and specifically pointed out in the claims.

In the drawings, Figs. 1 and 2 are side views, showing the improvement; and Fig. 3 is a section of the pulley, as will be described.

a represents the piano-string

a' represents an agraffe.

b represents the pulley, the eye *b'* of which is countersunk or rounded on either side, so the string will readily slip as the pulley is revolved, and also to prevent the string from being cut. This pulley is made convex on both faces, so the string will not engage the sides of the pulley as the latter is revolved in the operation of tuning.

b' is a groove in the periphery of the pulley.

c represents the tuning-pin, which I preferably make differential, as shown in Fig. 1—that is, with one portion having a larger diameter than the other.

d represents a stretching-wire. One end of this wire is secured to the smaller portion of the pin *c* and wrapped several times around

the same, and then carried around the pulley *b* and brought back and wrapped around the larger portion of pin *c* in the opposite direction from which it is wrapped around the smaller portion and secured, as shown. Thus by turning pin *c* so as to wind the wire *d* off the smaller portion of said pin onto the larger portion the piano-string will be gradually brought to the desired tension, a great delicacy of adjustment being secured by the use of the differential pin.

In Fig. 2 I show a modification in the manner of drawing the wire. In this construction I secure the string *d* to and wrap it several times around the pin, and carry it forward around the pulley *b*, and then back and secure it to a pin, or in any other manner desired. I prefer, however, to use the differential pin, as by it I secure a more delicate adjustment.

Having thus described my invention, what I claim, and desire to secure by Letters Patent, is—

1. The combination, with the string-plate and suitable framing, of the pulley *b*, the string *a*, having its end made fast to the pulley, a tension mechanism, and the stretching-wire *d*, passed around the pulley *b* and having its ends attached to the tension mechanism, substantially as set forth.

2. In a stringed musical instrument provided with a string-plate and suitable framing, the combination, with the string *a*, pulley *b*, and wire *d*, of the differential pin *c*, secured on the string-plate and having the opposite ends of wire *d* wrapped around its larger and smaller portions in opposite directions and secured thereto, substantially as and for the purposes set forth.

In testimony whereof I affix my signature in presence of two witnesses.

ALFRED J. GILLESPIE.

Witnesses:

C. McDANIELS,

FRANK A. GILLESPIE.
